ARTHUR W. THOMPSON, OF SHARON, PENNSYLVANIA, ASSIGNOR TO WESTINGHOUSE ELECTRIC & MANUFACTURING COMPANY, A CORPORATION OF PENNSYLVANIA

TRANSFORMER GROUNDING DEVICE

Application filed July 3, 1928. Serial No. 120,447.

My invention relates to electrical transformers and particularly to grounding switches therefor.

One object of my invention is to provide a grounding switch for transformers.

Another object of my invention is to provide a grounding switch for transformers that shall be operable from the extension of the transformer tank.

10 A further object of my invention is to provide a grounding switch for electrical apparatus that shall be retained in an inoperative position when the electrical device is energized.

15 In operating electrical transformers, it is desirable to ground the secondary winding when repairs are being made. Grounding switches should be so devised that it is impossible to ground the transformer when it is energized, in order to prevent accidental grounding during the normal operation thereof. Accordingly, I have devised a grounding switch that is operable from without the transformer tank only when the transformer is deenergized or providing an electromagnet that cooperates with a stop member for preventing operation of the grounding switch whenever the transformer is energized.

20 Referring to the accompanying drawings, Fig. 1 is a front elevational view of a grounding switch embodying my invention;

Fig. 2 is a diagrammatic view of circuits and apparatus embodying my invention;

25 Fig. 3 is a side view, partially in elevation and partially in section, of the grounding switch; and

Fig. 4 is an elevational view of a detail thereof.

30 Referring to Fig. 1, the illustrated embodiment of my invention comprises a bridging member 1 that is actuated into and out of engagement with stationary contact members 2 and 3 by a contact-controlling and supporting member 4 that in turn is operated by a cam mechanism 5 together with an electromagnet 6 that cooperates with a stop member 7 constituting a portion of the cam mechanism 5.

35 Referring to Figs. 2 and 3, the bridging member 1 is connected, by a conducting strap

8, to a metallic frame 9 that in turn, is secured by bolts 11 to a casting 12 which is secured, as at 13, by welding, to the wall of a transformer tank 14, so that the grounding switch is mounted internally of the transformer tank 14. Accordingly, when the bridging member 1 engages the contact members 2 and 3, the latter are connected to ground through the strap 8, the frame 9, the casting 12 and the tank wall 14. An extension 15 of insulating material is secured to the lower end of the frame 9 and supports the contact members 2 and 3.

40 The contact-controlling member 4 is provided with a pair of slots 16 and 17 that cooperate with a guide screw 18 and a roller 19, respectively. The roller 19 constitutes a portion of the cam mechanism 5.

45 The contact-supporting member 4 is provided with rollers 21 and 22 that engage the periphery of a cam wheel 23. The cam wheel 23 is mounted on a shaft 24 that extends outwardly through the casting 12 and terminates in an operating handle 25. Suitable packing 26 is provided to insure an oil-tight joint between the shaft 24 and the casting 12.

50 By reason of the provision of the rollers 21 and 22, the contact-controlling member 4 is moved upwardly and downwardly as the cam wheel 23 is turned.

55 The stop member 7 is mounted at the end of the shaft 24 and cooperates with an armature member 27 of the electromagnet 6. The armature 27 is biased in a clockwise direction by a tension spring 28. The electromagnet 6 is secured to the frame 9 by bolts 29. The armature 27 normally extends outside of the circumference of the circle described by the outer portion of the stop member 7, but, when it is attracted to its upper position by the solenoid 30 of the electromagnet 6 in opposition to the spring 28, it projects into the path of the stop member 7 and, accordingly, it is impossible to rotate the shaft 24.

60 Referring to Fig. 4, the operating handle 25 is provided, at its outer ends, with openings 31 that cooperate with an opening 32 in a lug 33 that is mounted on a plate 34 which is supported from the casting 12 and surrounds the shaft 24. The plate 34 is pro-

vided with indicia "grounded" and "alive". When the operating shaft 24 is moved, one of the openings 31 on the handle 25 is brought into registry with the opening 32, 5 and a padlock may be passed through the registered openings, thereby preventing unauthorized operation of the grounding switch.

Referring to Fig. 2, the contact members 10 2 and 3 are connected across the high tension winding 35 of the transformer, and the solenoid 30 of the electromagnet 6 is connected across the low voltage winding 36.

When it is desired to operate the grounding switch, the padlock securing the handle 25 to the lug 33 is removed, and pressure is applied to the handle 25. If the low-tension winding 36 is energized, the armature 27 will be in its upper position, thereby preventing movement of the stop member 7, 15 which is in its lower position when the bridging member 1 is raised. If the low-tension winding 36 is deenergized, the spring 28 contracts and the armature 27 is moved out of 20 the path of the lug 7; then the operator can turn the shaft 24 and thereby the cam wheel 25 the path of the lug 7; then the operator can 25 turn the shaft 24 and thereby the cam wheel 23.

Movement of the cam wheel 23 exerts pressure on the one or the other of the rollers 21 30 and 22, as the case may be, and forces the contact controlling member 4 upwardly or downwardly along its slots 16 and 17. When the member 4 is moved to its lower position, shown in Fig. 1, the bridging member 1 engages the contact members 2 and 3, thereby 35 connecting them, through the strap 8 and frame 9, to ground. When the grounding switch is in the grounded position, the word "grounded" is exposed on the plate 34.

40 When it is desired to put the transformer into operation, the handle 25 is turned to cover the word "grounded" and expose the word "alive". The cam wheel 23 then bears against the roller 22 to raise the contact-controlling member 4 and the bridging member 1 out of engagement with the terminals 2 and 3.

Accordingly, I have provided a grounding switch for electrical windings that may 45 be operated from a remote point, as from the exterior of a tank. Operation of the grounding switch is prevented so long as the winding is energized, due to the presence of an electromagnet that is energized in accordance with the connected electrical device, 50 and the armature of which cooperates with a stop member forming a part of the grounding switch.

It is to be understood that such changes 55 may be made in the arrangement, number and connection of the several parts of my invention as shall fall within the scope of the appended claims.

I claim as my invention:

60 1. The combination with windings of a

transformer, of a grounding switch for one of the windings and electro-responsive means associated with another winding for preventing the operation of the grounding switch when one of the windings is energized.

2. The combination with windings of a 70 transformer, of a grounding switch for one of the windings and means associated with another winding for preventing the operation of the grounding switch when the latter winding is energized.

3. The combination with windings of a 75 transformer, of a grounding switch for one of the windings and an electromagnet connected to another winding for preventing the operation of the grounding switch when the latter winding is energized.

4. The combination with primary and secondary windings in inductive relation, of a 80 grounding switch for the secondary winding and means associated with said primary winding for preventing the operation of the grounding switch when the primary winding is energized.

5. The combination with a high-tension 85 and a low-tension winding in inductive relation, of a grounding switch for the high-tension winding and an electromagnet connected to the low-tension winding for preventing the operation of the grounding switch when the latter winding is energized.

6. The combination with an electrical device comprising a tank and a winding, of a 90 grounding switch for the winding comprising a cam mounted within the tank, means for actuating the cam extending exteriorly of the tank and a contact-controlling member 95 actuated by the cam.

7. The combination with an electrical device comprising a tank and a winding, of a 100 grounding switch for the winding mounted within the tank comprising a cam, means for actuating the cam exteriorly of the tank and a contact-controlling member having a reciprocal movement imparted thereto by the cam.

8. The combination with an electrical device comprising a tank and a winding, of a 105 grounding switch for the winding mounted within the tank comprising a cam, means for actuating the cam exteriorly of the tank, a contact-controlling member having a reciprocal movement imparted thereto by the cam, and an electromagnet responsive to an electrical condition of said device 110 for preventing the operation of the cam when the electrical device is energized.

9. The combination with an electrical device comprising a tank and windings, of a 115 grounding switch for one winding mounted within the tank comprising a cam, means for actuating the cam exteriorly of the tank and a contact-controlling member having a reciprocal movement imparted thereto by the cam, and means controlled by 120

an electrical quantity in another winding for preventing the operation of the cam when the electrical device is energized.

10. The combination with windings of a transformer, of a grounding switch for one of the windings and means responsive to an electrical quantity of one of the windings for preventing the operation of the grounding switch when said last named winding is energized.

11. In combination, a transformer, a switch therefor comprising a longitudinally movable rod, locking means for said rod normally held out of operative position, and electromagnetic means for moving said locking means into operative position, said last named means being controlled by current in the low tension side of the line.

In testimony whereof, I have hereunto subscribed my name this 24th day of June, 1926.

ARTHUR W. THOMPSON.
